UNITED STATES PATENT OFFICE.

JULIUS CLOSSMANN, OF VIENNA, AUSTRIA.

SWITCH DEVICE.

Application filed May 15, 1923. Serial No. 639,034.

To all whom it may concern:

Be it known that I, JULIUS CLOSSMANN, a citizen of the Republic of Austria, and a resident of Vienna, Austria, have invented certain new and useful Improvements in Switch Devices, of which the following is a specification.

This invention relates to a switch device which is useful both for making and breaking electric circuits, and also may be used as a safety device or automatic circuit breaker when the current exceeds a certain amount.

The invention also relates to means to quench any arcing or sparking, and more particularly the invention has for its object to provide means whereby the ends of the arcs or sparks may be localized and so guided as to be quenched at a time when the ends of the arc are as far away from the initial contactual relation as possible so as to maintain the initial contact surfaces clear at all times, and to have any fusing if any occurs at points where such fusing is harmless.

Certain underlying features of the present inventions have been applied for in applications filed by me and H. Halberstadt, under Serial No. 607,441 and Serial No. 607,442, both filed on December 16, 1922, and reference thereto is hereby made.

The particular improvement, different in this application from the matter of the preceding applications, resides in the formation of the contact pieces so as to enable their co-operation with the arc to be such as to support the arc at the moment of its extinguishment, which arc has a tendency to follow the magnetic blow, but on the other hand desires to utilize the smallest distance between the parts.

The invention will be more fully described hereinafter, embodiment thereof shown in the drawings, and the invention claimed in the appended claims.

In the accompanying drawings, Figure 1 shows a longitudinal section of an apparatus in which my invention is embodied, taken on line 1—1 of Fig. 2;

Figure 2 is a plan view of an apparatus embodying my invention;

Figure 3 is a view taken from line 3—3 of Fig. 1;

Figure 4 is a section taken on line 4—4 of Fig. 2;

Figure 5 is a view of a modified form of contact piece, the view being similar to that of Fig. 3;

Figure 6 is another modified form of contact piece;

Figure 7 is a diagrammatic view of the contact pieces before their contacting;

Figure 8 shows the contact pieces brought together in contact, and before the current is turned on, the contact pieces being held together, for example, by a frictional hold;

Figure 9 shows the contact pieces after the current exceeds a predetermined amount, the distance between the parts being much exaggerated since in practice it is not visible to the eye;

Figure 10 shows the contact pieces just as they are separating, showing the arc as between the contact pieces;

Figure 11 shows the contact pieces separating still further with the arc broken off, and only the end parts thereof being shown in position; and

Figure 12 shows the contact pieces as they are separating with an illustrative diagram showing the arc, the current and magnetic lines of force.

Similar characters of reference indicate corresponding parts throughout the various views.

Referring to the drawings, and more particularly to Figures 1 to 4, the apparatus is provided with a slate base 11 which has the usual conductor 12 suitably secured to the slate base by a screw 13, and to which conductor 12 a thumb screw 13 is applied which serves to connect the conducting wire 15 with the conductor 12. Any connecting means such as are well known in the practical art may be used instead of this thumb screw.

The conductor 12 is provided with an upright 16 forming a fixed contact piece, for example, which will be more fully described hereinafter.

On the slate base, a second conductor 17 is provided which is again suitably secured to the slate base, and to which the conductor 18 may be applied by the thumb screw 19, or by any other connecting device.

The conductor 16 has connected therewith a frame 20 which is in circuit with the conductor 17, and this frame 20 supports core 21, for example, around which are wound convolutions 22 having in the embodiment shown in the drawings, for example, four or five turns, but one or more or no windings can be utilized. One end 23 of the wire or conductor forming convolutions or windings enters a slot 24 of the frame 20, so as to be anchored therein, to keep the spring action and the other end of the winding extends away from the frame in the form of a conductor arm 25, at the end of which a contact member 26 is secured. This contact member 26 will be more fully described hereinafter.

When the conductor arm 25 with its contact member 26 is in closed circuit position, as in full lines in Fig. 1, the conductor 25 serves to conduct the current passing through the circuit, but when the conductor with its contact is in the open circuit position, as indicated in dotted lines in Fig. 1, in the arm abutting against the shoulder the circuit is interrupted.

Referring now to the contact pieces 16 and 26;

The contact member 26 in the embodiment shown in the drawings, Figs. 1 to 5, consists of a body of revolution in the form of a cone with the axis of this cone co-axial with the axis of the conductor arm 25. Instead of the cone, a semisphere or half cylinder can be utilized.

Referring to Figures 3 to 5, it will be seen that the conductor arm 25 is co-axial with the contact piece 26. The base of the cone is perpendicular to the conductor arm 25, as shown in Figures 1 and 2, in which these parts are preferably at right angles to each other. The other contact piece 16 in the embodiment shown in the drawings, Figures 1 to 3, has a recessed or slotted portion 50 at the upper part of the upright 16, and the walls 27 and 28 diverge or incline from the portion 29.

The upright 16 up to the portion indicated by the line 30 is perpendicular to the plane of the slate base, and at any rate is a flat surface, so as to match with the base of the contact piece 26 so that when the contact piece 25 rests against the upright 16 the flat surface of the piece 26 and the flat surface of the upright 16 will intimately contact, and as a result they will, in view of their parallelism, create a frictional contact of a closely hugging character which must be overcome before the parts 65 are separated. In other words, the surfaces

are so arranged that a frictional contact is obtained when one surface is pressed upon the other. This may be augmented by a spring tension. This is preferably done by forcing the contact piece 26 along the upright 16 against the action of the spring until a spring tensioned frictional hold is obtained; and in some cases also by a slight toggle action relationship.

The spring tension in the embodiment shown in the drawings is obtained by the turns given to the conductor in the form of a solenoid shaped spiral winding, and also in the arrangement of the arm 26 in respect to these turns. In other words, when the arm 25 is placed in the position shown in full lines in Figure 1, a certain amount of spring tension is overcome by pressure applied by the hand or by mechanical means. The parts 16 and 26 are frictionally held in position, by the base of the contact 26 coinciding with the contact 16 until the flat surfaces match, which gives the best full surface contact.

The member 16 is provided upwardly from the line 30 with a bevelled portion, shown in Figure 1 by 31, so that the upright 16 does not impede the general circular movement of the contact piece 26, when moving into open position.

It may be said that the base of the cone rides on the surface 31 when going to closed position which is inclined or bevelled, and as it rides the spring is tensioned, this riding taking place until the base matches with the surface of the contact 16, or until the base is below the line 30, the relative position of the parts being such as to bring about a clamping or locking action of a relatively slight character, but sufficient to hold the parts in contacting position.

Rearwardly of the upright 16 it is also provided with a bevelled surface 32. From this bevelled surface project members 33, which on their uppermost surface incline downwardly. These members 33 have their innermost edges or surfaces, indicated by 35, diverge from a median line or from the inclined surfaces 27 and 28, as is clearly seen in Fig. 2.

The action of these parts just described is to so guide the arc during the separation of the contacts after their contactual relationship is discontinued by the surfaces described in the most favorable manner, and to the most favorable position for the end of the arc at the moment when the arc is quenched. The member 26 is preferably cone shaped or brought to a point as shown, so as also to guide the other end of the arc from the edge of the base to the point thereof, during the separation of the contacts after their contactual relationship is discontinued.

In Fig. 5 there is shown an embodiment

in which the inclined surfaces 27 and 28 are omitted. The arm 25 rests on the base of the slot. The effectual initial contact surface is shown by 38. The straight surface 5 extends to 30.

In Fig. 6, a single part contact member is shown, in which the effectual contact surface or initial contact surface is shown at 46, the arm 25 resting on the shoulder 47. The surface 41 inclines rearwardly to the edge or peak 43.

The operation of the device is the following:

When the parts are in the position shown 15 in Fig. 1, with the arm 25 in the position shown in dotted lines, the current is naturally interrupted.

The arm 25 is then taken manually though 20 it can also be suitably mechanically operated, and is moved into the position shown in full lines in Fig. 1, and in order to hold it in position a frictional hold is obtained. The spring tension which is overcome to the 25 extent of forcing the base of the contact 26 against the flat surface of the upright 16, augments the hold. Thereby this contact and pressure holds these parts mechanically in position. The current of usual or normal 30 then passes through these parts, and as a result of this, the contact piece 26 is forced still further tightly against the flat surface of the upright 16 and the contactual relationship is made still more effectual and intensive, and the electrical resistance between 35 the contacting parts is thereby reduced to the lowest. These hitherto unknown physical appearances are founded upon complicated actions of the currents and their strengths, as well as the thereby formed 40 complicated electrical and magnetic fields.

This further tightened effect may be due 45 to the action of the current upon the windings, whereby the convolutions are tightened, or to the magnetic field produced by the windings, or the current field surrounding the arm 25 or due to electrical actions in the connecting parts, or altogether when the current flows through the circuit in either direction.

50 During the normal operation of the device the parts function in the manner described, both the frictional hold and the tightened effect holding the contact member 26 in the position shown in full lines in Fig. 1.

55 When, however, the current exceeds a predetermined amount, it acts partly due to the Joule effect upon the arm 25 and upon the convolutions so that the contact member 26 is moved away from the upright 16. This 60 movement of the contact away from the upright, overcomes the pressure of the parts against each other. This is but a slight effective movement, and not visible to the eye, but is shown in exaggerated manner in Fig. 65 9, and is sufficient to release the frictional

hold between the flat surface of the upright 16 and the base of the contact 26. The friction is decreased sufficiently to release the parts, and permit the contact 26 to move under the spring action, but an efficient contact 70

is maintained between the contact members, so that between the parts no arc or sparking is formed. From the initial position to the 75 position of the parts where contactual relations terminate there is a continual change in the places of engagement of the contacts until actual separation takes place as in

Fig. 10. This continual change results in preventing arcing at the initial point of contact. Any arc that is formed is at points 80 other than at the initial contact points. At the separating point, as in Fig. 10, the arc is never at rest so no burning or fusing can take place.

Whatever friction there is during the relative movement is overcome by 85 the spring action. The lateral inclination of the sides of the slot and the division of the current into two parts by the two members, serves to bring about a right angled relationship of the contact area. 90

In Fig. 10 the member 26 is shown just as it separates from contactual relationship with the member 16, and hence an arc is formed. In Fig. 11 the arm with its contact 26 is moved slightly further and shows how one 95 end of the arc has been guided along the inclined surface 33 to the rearward peak 33^a thereof, and the other end of the arc has been guided to the peak or apex of the cone. The lines of force (not shown) which surround the inclined surface projection press 100 the arc to the peak 33^a.

It will be noted from the description and drawings that this surface 33 is brought 105 rearwardly of the effective contacting surface of the contact members which is indicated by 38 in Fig. 1, and which in Figs. 2, 3 and 5 may be said to be that portion of the contact member 26 which is shown in dotted lines below the line 30. This is the intial and compact contact surface.

Due to the bevelled surface 31 and the bevelled surface 33, together with the bevelled surface 35, the two arcs are split away from each other, and as far away from each other as possible, and as far away as practical from the effective contact surface or contact when at rest as at 38. At the same time, it will be noted that the other end of the arc takes the position towards the peak of the cone, indicated by 39 in Fig. 11, and also as far away as possible from the effective contact surface 38 and from the base of the contact member 26. 115 120

The provision of these guiding surfaces for the ends of the arc brings about the location of these ends at points, where they rest until the arc is finally broken or quenched. Any slight fusing of the metal 125 is at the peaks and at as great a distance as 130

possible and practical from the effective contact surface 38. This assures, together with the rubbing action of the effective contact surfaces, a clean effective contactual surface 38. It is, of course, also true that as the member 26 moves along the contact member 16 the contactual relationship of the parts continually changes until the parts separate, and this again insures that no arcing takes place at the effective surfaces.

It has been stated that the arc is divided into two parts because they are two members on the contact member 16, but it is of course clear that should it be found desirable that only one member be used as in Fig. 6, there would be only one arc. In case only one member is used, the variation of the contactual relationship of the parts would be continually carried out so as to insure at the effective contact surface, a clean surface at all times.

In Fig. 12, I have shown in the most general manner some of the theories underlying the operation of the device; but in view of the well-known complexity of the action of fields of force and the current-line movement during the entire switching positions in relationship to the moving parts, or vice versa, it will be clear to any one skilled in the art that such explanation of the theory should not be considered complete as, from a scientific standpoint, considerable may be added thereto, both from a known source, and from such sources as may be discovered by scientists in the future.

I give these only generally to make clear the general action, particularly as it is almost impossible to indicate diagrammatically all of the actions which result from movements of the parts in fields of magnetic forces and from the fields of the current.

Referring to Fig. 12, I have shown the contact members 16 and 26 separated still further from the position of the parts shown in Fig. 11. The arm 25 has its field due to the current passing therethrough, and this serves to blow the arc 40 in a direction away from the contact member 26, and the lines of force 59 of the magnet field of the convolutions serve also to blow the arc in substantially the same direction. The resultant of the field of the arc when initially formed, as for instance as in Fig. 10, and the field 59, is about as indicated by 52, and extends the arc 50 into loop form. Arrows 51 and 60 indicate the direction of the current. It can be in either direction. When the arc is so blown, the field of force of the arc itself has one direction, as indicated by the arrow 59, and the upper portion of the arc has the field of force acting in the same rotary direction, as the lower part of the loop, but because it is superposed upon the lower part of the arc the relative rotation is in opposite direction. As these are in opposite directions the stresses

serve to separate the arc loop, as indicated by the arrows 55 and 56.

It is believed that the action of such forces serve on the one hand to elongate the arc and to operate to blow it and quench it thereby, and as a result of such forces which are believed to operate, it has been found that very high excess currents and potentials may be utilized with the relatively small device described and shown, because the arc which otherwise would be injurious is so manipulated as to make it harmless.

During the action just described, the ends of the arc have been found to be most efficiently guided by the surfaces 33 of the contact 16 and the conical surface up to point 39 of the contact 26, and it has been found by repeated operations of devices of the kind described with high excess current and tensions that no deterioration of the contacts takes place, and it has also been found that with such excess currents and tensions the parts do not melt, including the part 25, because the excessive currents and tensions are interrupted in their flow by the counter electromotive forces produced, which subdue the excessive currents and tensions and quench or extinguish the arc and render it innocuous.

Neither the arm 25, nor its field of force, nor the arc and its field of force, nor the field 59, is stationary, but variations occur constantly, and the arm 25 and arc 58, cut lines of force, and the various lines of force cut each other. The velocity of movement of the arm 25 and arc 58 has also an effect. As a result of these and other actions, a counter electromotive force is set up as indicated by the arrow 59', which acts against the flow of the current when moving in the direction of the arrow 51, and this suppresses and destroys the arc during the time it is actuated in the manner described.

During the separation described the arc moves from the position shown in Fig. 10, to that indicated by Fig. 11. One end moves along surfaces 31 and 33 to the point 33^a, and the other end from the edge of the base of the cone 26, along its side, to the peak point 39 thereof. The arc naturally has the tendency to go through the shortest distance between the parts, but on the other hand is acted upon by the blowing fields. And the form given to the parts is such to follow on the one hand the movements of the ends of the arc, and on the other hand, to provide means for guiding the arc during the separated movement of one contact in respect to the other, as far as possible away from the initial contact surface 38, and from the contactual surfaces during the time the contact members move relatively to each other. The ends of the arc have substantially no effect upon the points 33^a and 39, because before any fusing or burning can take place

the arc is quenched, or in other words the attenuated form of the arc prevents it from exerting a fusing effect upon the points.

It, of course, must be remembered that if 5 two members are used there would be two arcs, each operating generally in the manner described, and the fields of forces thereof would bring about very complex relations, and when two members are used, the other 10 contact member bridges the two members.

Part or all of the arm 25, may be made of a material which readily fuses, so that in the event that a blocking of the contacts 16 and 15 26, takes place the fusible part of the arm 18 will melt and break the circuit.

The dimension of the wire, the diameter 20 of the coil, and the number of turns of the coil or convolutions may be such that the opening of the circuit only takes place after 25 a definite time, so that a time switch is obtained.

I have shown embodiments of my invention, but it is clear that changes may be made 30 therein without departing from the spirit 25 of the invention.

What I claim as new is:

1. In an electric device, a contact member 35 having an effective contact surface at one side thereof and having an arc guiding 30 projection extending away from the effective contact surface on the other side of the contact member, and a second contact member adapted to be contacted with the effective contact surface of the first contact without contacting with the arc guiding 35 projection, the plane passing through the effective contact surface of the first contact member being perpendicular to the plane of the path of movement of the 40 second contact member.

2. An electric device, comprising a contact member having an effective contact surface at one side thereof, an arc guiding projection 45 extending from the other side thereof and provided with a downwardly inclined surface, and a second contact member adapted to be contacted with the effective surface contact surface of the first contact without contacting with the arc guiding 50 projection.

3. In an electric device, comprising a contact member having an effective contact surface at one side thereof, an inclined surface 55 inclined away from the effective contact surface rearwardly of a member, a second inclined surface inclined rearwardly of the first inclined surface, and a second contact member co-operating therewith.

4. In an electric device, comprising a contact member having an effective contact surface at one side thereof, an inclined surface inclined away from the effective contact surface rearwardly of the member, a second inclined surface inclined rearwardly 60 of the first inclined surface, and a third sur-

face inclined away from the central portions of the member, and a second contact member co-operating therewith.

5. In an electric device, comprising a contact member having an effective contact surface at one side thereof, a part extending towards the outer side thereof and provided with a downwardly inclined surface, and a second contact member having a conical member the base of which co-operates 70 with the effective contact surface of the first contact member. 75

6. In an electric device, comprising a contact member having an effective contact surface at one side thereof, an inclined surface inclined away from the effective contact surface rearwardly of the member, a second inclined surface inclined rearwardly of the first inclined surface, and a second contact member having a conical shape with 80 the base of the conical member co-operating 85 with the effective contact surface of the first contact member.

7. In an electric device comprising a contact member having an effective contact surface at one side thereof, an inclined surface inclined away from the effective contact surface rearwardly of the member, a second inclined surface inclined rearwardly of the first inclined surface, a third surface inclined away from the central portion of the member, and a second contact member having a conical shape with the face of the conical member co-operating with the effective contact surface of the first contact member. 90 95 100

8. In combination, a contact member having an effective contact surface at one side thereof, and an inclined projection diverging therefrom at the other side thereof for guiding the arc, a pivoted unitary spring and homogeneous current carrying arm, and a contact member on the arm having an effective contact surface for contacting with the effective contact surface of the first contact member without contacting with the arc guiding projection. 105 110 115

9. In combination, a contact member having a flat effective contact surface at one side thereof, a projection at the other side thereof of extending rearwardly, downwardly, and outwardly of the first contact, a unitary spring and current carrying arm, and a contact member on the arm co-operating with the first contact member and having an effective contact surface adapted to be brought in contact with the effective surface of the first contact member without contacting with the projection. 120

10. In combination, a unitary spring and current carrying member, a convolution connected with the member, contact pieces, means for energizing said parts for creating fields of force around the member, convolution and contact pieces, means on the con- 125 130

tact pieces for contacting with each other, and means on the contact pieces for guiding the arc, while acted upon by the fields of force to points distant from the contacting surfaces of the contact pieces.

- 5 11. In combination, electric contact members for closing an electric circuit and for opening the same, and means for guiding the ends of the arc formed by the separation 10 of the contact members during the attenuation of the arc by the separation of the contact members along places most favorable to the arc ends during its attenuation, the arc guiding means not contacting with each 15 other.
12. In combination, contacting means for closing and opening an electric circuit, and each having tapered means with their peaks in opposite direction to each other, said tapered means not contacting with each other.

- 20 13. An arc preventing device, electrical contact members, having effective contacting surfaces in conformity with the path of movement of one of the members and having 25 arc guiding means in surfaces substantially perpendicular with the effective contact surfaces.

- 30 14. An arc preventing device, an electrical contact member, having an effective contacting surface, and having an arc guiding means in a plane substantially perpendicular with the effective contact surface, and a second contact member having an effective contact surface, contacting with that of the 35 first contact surface, the contacting surfaces being substantially perpendicular with the arc guiding means plane.

- 40 15. An arc preventing device, comprising an electrical contact member, having an effective contacting surface, arranged in a plane, and an arc guiding projection arranged in a plane substantially perpendicular to that in which the contacting surface is arranged, and a second contact member.

- 45 16. An arc preventing device, comprising

an electrical contact member, having an effective contacting surface, arranged in a plane, an arc guiding means in a plane perpendicular to the plane of the contact, a movable member for said contact member movable in a plane perpendicular to the plane of the contact member and plane of the arc guiding means.

50 17. An arc preventing device, comprising an electrical contact member, having an effective contacting surface at one side thereof, an arc guiding means at the other side thereof arranged in a plane substantially perpendicular to the contacting surface, and extending away from said surface, and a 55 second contact member.

60 18. An arc preventing device, comprising an electrical contact member having an effective contacting surface, means thereon for guiding the arc along the path of its tendency, said means being elongated, and a second contact member.

65 19. An arc preventing device, comprising a contact member, a member for said contact member, a spring convolution for said member, means on said contact member for guiding the arc, and a second contact member contacting with the first contact member without contacting with the arc guiding means.

70 20. An arc preventing device, comprising a contact member, a member for said contact member, a spring convolution for said member, the axis of the spring convolution being perpendicular to the path of movement of the member, an arc guiding means for said contact member, and a second contact member contacting with the first contact member without contacting with the arc guiding means.

75 In testimony that I claim the foregoing as my invention, I have signed my name hereunder.

JULIUS CLOSSMANN.
